UNITED STATES PATENT OFFICE.

EDISON C. ROBINSON, OF TELLURIDE, COLORADO.

ORE-CLASSIFIER.

1,223,523.

Specification of Letters Patent. Patented Apr. 24, 1917.

Application filed May 15, 1916. Serial No. 97,627.

To all whom it may concern:

Be it known that I, EDISON C. ROBINSON, a citizen of the United States of America, residing at Telluride, in the county of San Miguel and State of Colorado, have invented 5 certain new and useful Improvements in Ore-Classifiers, of which the following is a specification, reference being had therein to the accompanying drawing.

10 This invention relates to an ore classifier and has for its principal object the production of a device which is constructed so as to cause the several grades or sizes of ore to be separated and passed into different receptacles.

Another object of this invention is the production of an ore classifier wherein there is provided a rotating spiral which is adapted to fit upon a conical bottom, where 20 by the movement of the spiral will not cause the largest crushed ore within the tank to be too greatly agitated, thus permitting the coarser ore to be drawn to a position to be discharged through a central pipe, while the 25 finer ore will pass around a baffle used in connection with this device so as to pass into a launder or trough.

Another object of this invention is the production of an ore classifier which has a 30 baffle adjustably mounted therein, this baffle being constructed in the form of a sleeve so that upon its adjustment the size of ore which passes from the tank into the launder or trough may be regulated, for as 35 this ore passes into the launder or trough it may be conveyed by gravity or otherwise to wherever desired.

Another object of this invention is the production of an ore classifier having a feed 40 pipe carried within the tank, whereby the crushed ore and water mixture may be passed into the tank adjacent the lower portions thereof.

A still further object of this invention is 45 the production of an ore classifier wherein the rotating spiral is constructed so that as the ore is moved along the bottom by the spiral it will assume a trough-like formation so that the water may readily and easily 50 run from the ore as the same is passed upwardly and deposited in a central discharge pipe extending from the central upper portion of the conical bottom.

With these and other objects in view this 55 invention consists of certain novel combinations, constructions, and arrangements of

parts as will be hereinafter fully described and claimed.

In the accompanying drawings:

Figure 1 is a side elevation of the ore 60 classifier as constructed in accordance with this invention.

Fig. 2 is a horizontal section through the ore classifier taken on the line 2—2 of Fig. 1, looking in the direction of the arrows. 65

Fig. 3 is a central vertical section through the ore classifier.

Fig. 4 is a fragmentary plan view of a portion of the spiral and the spider connected thereto, illustrating how the spiral 70 extends across the spider.

Fig. 5 is a fragmentary plan view of a portion of the device, showing the manner in which the baffle is retained by means of the set screws in an adjusted position with- 75 in and extending above the tank.

Fig. 6 is a section taken on the line 6—6 of Fig. 5.

Fig. 7 is a plan view of the operating lever, which is connected to the device so as 80 to lift the arm which rotates the spiral.

Referring to the accompanying drawings by numerals it will be seen that the ore classifier comprises a tank 1 which is preferably 85 formed of sheet metal and which is circular in shape, as shown in Fig. 2, thereby making a greater overflow contact for the solution used in the operation of the device. This tank 1 has a conical bottom 2 extending from the lower portions thereof upwardly toward 90 the central portion of the tank. This bottom 2 has its upper end cut away as shown at 3 so as to permit the flange 4 of the internally threaded thimble 5 to be attached thereto by means of the rivets 6. The central 95 discharge pipe 7 is threaded into engagement with the internally threaded thimble 5 as shown in Fig. 3 for purposes to be hereinafter set forth.

The circular feed pipe 38 which constitutes the feed pipe is provided with the apertures 39 and this feed pipe 38 is supplied by means of the supply pipe 40 extending from the housing 41 mounted upon the block 42 carried by the platform 15. 100 This pipe 40 constitutes a support for the pipe 38 while the rods 43 carried by the block 42 are also connected to the pipe 38 for further supporting the same. The pipe 44 supplies the housing with water and 105 crushed ore when the device is in operation. It is intended that the crushed ore and wa-

ter will pass through the pipe 44 into the feed pipe 38 and then be dispensed or injected into the tank through the apertures 39.

5 The spider 11 has its two downwardly diverging arms 12 extending into the interior of the tank 1 at a spaced distance from the outer surface of the bottom 2. The double spiral 13 is positioned so as to rest 10 upon the conical bottom 2 and is coiled so as to extend from the lower portion of the bottom 2 to a point adjacent the upper end 3 thereof as shown in Figs. 2 and 3. The arms 12 of the spider 11 fit upon the spirals 15 13 and these spirals may be secured to these arms 12 by being bolted or secured in any other suitable manner thereto, so that as rotary motion is imparted to the spider 11 the spirals may also be caused to rotate upon 20 the conical bottom 2 for purposes to be hereinafter set forth. The shaft 14 is secured in any suitable manner to the spider 11 and passes upwardly through the platform 15. The large bevel gear 16 is keyed upon the 25 shaft 14 by the spindle key 17 and meshes with the small bevel gear 18 carried by the operating shaft 19 supported by the bracket 20. Thus, it will be seen that as the shaft 19 rotates the rotary motion imparted to the 30 bevel gear 16 by means of the bevel gear 18 will cause the shaft 14 to be rotated, thus imparting rotary motion to the spider 11 and thence to the spirals 13.

The lugs 21 are positioned upon the upper edge of the tank 1 and are held in position by means of the rivets 22. The set screws 23 pass through these lugs 21 and bear upon the exterior surface of the baffle 24. This baffle 24 is formed so as to present a sleeve-like structure fitting within the tank 1, although extending for a distance thereabove whereby the set screws 23 bearing upon this baffle 24 will hold the same in an adjusted set position. Thus, it 45 will be seen that this baffle 24 is capable of vertical adjustment when necessary.

When this ore classifier is in operation the crushed ore and water are injected into the tank 1 from the feed pipe 38 which is supplied by the pipe 40. It should be understood that the term "water" as herein used is usually a solution, water and cyanid of potassium or sodium. This solution facilitates separating the fine ore from the coarse ore so that the cyanid may have a better chance to dissolve the smaller particles of metal in the ore, while the coarse ore may be conveyed to a regrinding machine to be ground as fine as necessary to be associated 55 with the cyanid solution.

It is, of course, obvious that at this time rotary motion should be imparted to the shaft 14 by the gears 16 and 18 through the shaft 19 so that the spider will cause the spirals 60 13 to be rotated upon the conical bottom

2. If it is only desired to have very fine ore passed over the upper edge of the tank 1 together with the water so as to pass into the launder or trough 25 the baffle 24 should be adjusted so as to extend for a considerable distance down into the tank 1. It will be seen, of course, that the outer surface of this baffle 25 is held at a distance beyond the inner surface of the tank 1, whereby the water, together with the fine particles of ore 70 will pass upwardly between these two elements so as to overflow into the launder or trough 25. The water and fine ore may then be conveyed in any suitable manner from the launder or trough to wherever desired. 75 As the spirals continue to rotate upon the conical bottom 2 the larger particles of ore will be dragged into a spiral formation upon the bottom 2 toward the upper end of the bottom. When the coarse ore finally 80 reaches this point it will be urged into the discharge or exhaust pipe 7 to be conducted to the regrinding mill, as above set forth. Since the movement of the spirals 13 and the arms 12 of the spider 11 will continue 85 when the ore classifier is in operation fine ore will be suspended in or through the water. It will be noted further that owing to the fact that the spirals extend toward the lower portions of the bottom 2 and also toward the upper portions that although the spirals will be filled with coarse ore gutter-like formations will be formed by the ore 90 upon the spirals so that the water in the ore can readily run around the spirals and 100 drain down into the interior of the tank 1 so that only a minimum amount of water will be discharged through the pipe 7. Therefore, since the fine particles of ore will 105 be suspended in the water this fine ore and water must necessarily pass between the baffle and the interior of the tank so as to overflow into the launder or trough 25. By adjusting the baffle 24 and moving the same upwardly in a vertical plane a greater space 110 will be provided between the spirals and the lower edge of the baffle 24 and as a consequence ore of a greater size may pass to the upper edge of the tank into the launder or trough than would be the case if the baffle 115 24 were carried so as to extend for a greater distance into the interior of the tank.

The platform 26 has a journal bracket 27 mounted thereon, which is retained in position by means of the screws 28 which pass 120 through the openings 29. The lever 30 has the integral ring 31 formed upon one end thereof and this ring 31 is split so as to provide the parallel arms 32 fitting upon the journal bracket 27 being retained by means 125 of the pivot 33. The ring 31 passes about the grooved collar 34 which is keyed upon the shaft 14 by means of the set screws 35. The lugs 36 carried by the ring 31 opposite each other fit within the grooved collar 34 as 130

shown in Fig. 7. The platform 26 is provided with a slot 37 through which depends the lever 30 which is substantially L-shaped as shown in Fig. 3. Thus, it will be seen that when so desired the lever 30 may be pulled away from the shaft 14 thus causing the lugs 36 to lift the collar 34 which will in turn lift the shaft 14. In order to permit this movement it will be seen that the key 17 is carried in the elongated slot 17' and as a consequence the upward movement of the shaft 14 is not interfered with. This action of the shaft will cause the spider 11 to be lifted whereby the arms 12 will lift the spirals 13 from engagement with the bottom 2. This action may be desired when the machine is not running when free access is desired to the interior of the tank 1. Of course, at this time it is obvious that the baffle 24 must be lifted high enough to permit the upper movement of the arms and the spirals. If at this time the machine is again started to operate, the releasing of the lever 30 will cause the spirals to move down on to the ore carried upon the bottom 2 and to dig this ore away until the spirals rest snugly upon the bottom 2, as shown in Fig. 3.

From the foregoing description it will be seen that a very efficient ore classifier has been provided which is constructed so as to permit the crushed ore and water to be injected into the interior of the tank. After this action it will be seen that the coarse ore may be moved upwardly and finally discharged through the exhaust pipe, while the water and the finer ore is thoroughly mixed and will pass around the baffle carried in the tank so as to overflow the interior of the tank into the launder or trough. It is further obvious that upon the adjustment of the baffle the ore of a greater size instead of being discharged through the discharge pipe may pass over the upper portion of the tank into the launder or trough, while the construction of the spirals will cause a maximum amount of water to run back along the gutter-like formation caused by the tilting of the spirals, as shown in Figs. 2 and 3, thereby necessitating the greater amount of water in which the fine ore is mixed to be passed into the launder or trough.

The circular pipe 8, which constitutes the flushing pipe has apertures 9 registering with the apertures 9' formed in the conical bottom 2 adjacent the lower portion thereof and this flushing pipe is supplied with water through the pipe 10 so that when it is desired to flush the tank for cleaning the same this action may be easily accomplished.

60 What is claimed is:

1. In an ore classifier of the class described, the combination of a tank having a conical bottom, said bottom extending evenly from its lower portion to its upper portion, thereby presenting an even bearing

surface, said bottom having an outlet at its upper portion, means for supplying said tank with crushed ore and water, a rotating spider having arms extending into said tank, means for supporting and rotating said spider, spirals secured to said arms, each spiral formed from a ribbon-like strip of material coiled to form a plurality of convolutions, said convolutions diminishing in size toward the upper end of the spiral, said convolutions being spaced apart at greater distances than the width of said ribbon-like strips, thereby providing sufficient space for coarse ore, and said spirals resting evenly upon said conical bottom throughout their entire length, whereby ore will be dragged up said conical bottom as said spirals are moved by said arms.

2. In an ore classifier of the class described, the combination of a tank having a conical bottom, said bottom extending evenly from its lower portion to its upper portion, thereby presenting an even bearing surface, said bottom having an outlet at its upper portion, means for supplying said tank with crushed ore and water, a rotating spider having arms extending into said tank, means for supporting and rotating said spider, spirals secured to said arms, each spiral formed from a ribbon-like strip of material coiled to form a plurality of convolutions, said convolutions diminishing in size toward the upper end of the spiral, said convolutions being spaced apart at greater distances than the width of said ribbon-like strips, said ribbon-like strips extending at right angles to the surface of said bottom, whereby as said spirals are moved around upon said bottom they will rest snugly thereon for dragging ore upon said bottom and furthermore said spirals will form gutter-like structures for causing water to run back therealong into said tank.

3. In an ore classifier of the class described, the combination of a tank having a conical bottom, said bottom extending evenly from its lower portion to its upper portion, thereby presenting an even bearing surface, said bottom having an outlet at its upper portion, means for supplying said tank with crushed ore and water, a rotating spider having arms extending into said tank, means for supporting and rotating said spider, spirals secured to said arms, each spiral formed from a ribbon-like strip of material coiled to form a plurality of convolutions, said convolutions diminishing in size toward the upper end of the spiral, said convolutions being spaced apart at greater distances than the width of said ribbon-like strips, thereby providing sufficient space for coarse ore, said spirals resting snugly upon said even conical bottom throughout their entire length, whereby ore will be dragged up said conical bottom as

said spirals are moved by said arms, and means for lifting said spirals from engagement with said bottom whenever necessary.

4. In an ore classifier of the class described, the combination of a tank having a conical bottom, said bottom extending evenly from its lower portion to its upper portion, thereby presenting an even bearing surface, said bottom having an outlet at its upper portion, means for supplying said tank with crushed ore and water, a rotating spider having arms extending into said tank, means for supporting and rotating said spider, spirals secured to said arms, each spiral formed from a ribbon-like strip of material coiled to form a plurality of convolutions, said convolutions diminish-

ing in size toward the upper end of the spiral, said convolutions being spaced apart at greater distances than the width of said ribbon-like strips, thereby providing sufficient space for coarse ore, said spirals resting snugly upon said even conical bottom throughout their entire length, whereby ore will be dragged up said conical bottom as said spirals are moved by said arms, and a lifting lever connected to said last-mentioned means, whereby said spirals may be lifted from engagement with said bottom when necessary.

In testimony whereof I hereunto affix my signature.

EDISON C. ROBINSON.
